UNITED STATES PATENT OFFICE.

THOMAS P. GREGER, OF PHILADELPHIA, PENNSYLVANIA.

DESIGN FOR A MANHOLE-COVER.

SPECIFICATION forming part of Design No. 30,632, dated April 25, 1899.

Application filed March 30, 1899. Serial No. 711,169. Term of patent 14 years.

To all whom it may concern:

Be it known that I, THOMAS P. GREGER, a citizen of the United States, residing at the city of Philadelphia, in the county of Philadelphia and State of Pennsylvania, have invented and produced a new and original Design for a Manhole-Cover, of which the following is a specification, reference being had to the accompanying drawings, forming part hereof, in which—

Figure 1 is a top or plan view of a manhole-cover, showing the particular shape or configuration of the cover of my said design; and Fig. 2 is a vertical sectional view on the line xx of Fig. 1, these two views being deemed essential to a proper disclosure or illustration in detail of the leading feature of my design invention, consisting of the shape or configuration of the manhole-cover.

Referring to the drawings, the circular cover A is substantially dish-shaped in cross-section, and the projecting peripheral wall a of which on the inner surface in outline is formed with convex and concave ornaments a' and a'' to about the middle of the cover on both sides, in which convex-shaped ornamental surface outlines a^3 and a^4 are provided, and

transversely to these ornamental surface outlines are T-shaped ornamental depressions or openings a^5 and a^6 , the openings of which extend through the wall of the cover to form right-angular openings a^7 , in which complementary-shaped lift-bars b are inserted and having angular ends b' , as clearly illustrated in Fig. 2. In the surrounding convex ornamental outline surface a' of the cover are provided at defined distances apart cone-shaped openings extending through the wall of the cover. In the outer peripheral rim of the cover are provided W-shaped ridges c' , as clearly illustrated in Fig. 2 of the drawings.

Having thus described the nature and objects of my invention, what I claim as new, and desire to secure by Letters Patent, is—

The design for a manhole-cover, substantially as herein shown and described.

In testimony whereof I have hereunto set my signature in the presence of two subscribing witnesses.

THOMAS P. GREGER.
